UNITED STATES PATENT OFFICE.

LLOYD S. JOHNSON, OF DAYTON, OHIO, ASSIGNOR TO HORACE M. HUFFMAN, OF DAYTON, OHIO.

BURNER FOR BLOWTORCHES, FIRE POTS, AND THE LIKE.

Application filed August 12, 1925. Serial No. 49,701.

This invention relates to burners for blow torches, fire pots and the like.

One object of the invention is to provide a burner of this kind which will produce an 5 intensely hot blue flame.

A further object of the invention is to provide such a burner in which the flow of fuel to the burner will be uniform and the flame steady.

10 A further object of the invention is to provide a burner of this character which will be simple in its construction and inexpensive to produce.

15 Other objects of the invention will appear as the device is described in detail.

In the accompanying drawings Fig. 1 is a side elevation of a burner embodying my invention, showing a portion of the fuel tank in section; Fig. 2 is a longitudinal sectional view taken centrally of the burner; Fig. 3 is a transverse section taken on the line 3—3 of Fig. 2; Fig. 4 is a transverse section taken on the line 4—4 of Fig. 2; and Fig. 5 is a front elevation of the burner.

20 In these drawings I have illustrated one embodiment of my invention but it will be understood that this has been chosen for the purpose of illustration only and that the burner may take various forms without departing from the spirit of the invention.

25 As here illustrated the burner comprises an elongated body portion or flame tube 1 which is provided in its rear wall with an inlet port 2 which is controlled by a needle valve 3 screw threaded into a boss 4 formed on the rear end wall of the burner. In the present arrangement the burner is supported on the fuel tank 5 by means of a tubular supporting member or pipe 6 which forms a 30 part of the supply pipe and the lower end of which communicates with a tube 7 which extends downwardly into the fuel tank, preferably to a point near the bottom thereof, the tube 7 and pipe 6 being preferably 35 filled with wicking, as shown at 8. The tank 5 is provided with the usual air pump 9, by means of which air may be pumped into the tank to subject the liquid fuel therein to air pressure which will force it from the 40 tank into the burner. The upper end of the supply pipe 6 communicates with one end of the fuel conduit which leads therefrom to the intake port 2 and is so arranged that it 45 will be subjected to the heat of the flame in the flame tube. As here shown, the conduit

is formed integral with the flame tube and comprises a portion 10, communicating with the upper end of the pipe 6 and extending through the flame tube transversely to its length, the conduit being of an exterior diameter less than the internal diameter of the flame tube so as to provide relatively large passageways for the flame on both sides of the conduit. A second portion of the conduit is formed in the top wall of the flame tube, as shown at 11, and extends rearwardly from the portion 10 of the conduit to the rear wall of the flame tube where it is connected with a vertical portion 12 of the conduit which is formed in the rear wall and 50 leads to the inlet port 2, the top and rear walls of the flame tube being thickened to provide space for the conduits. The bore in the rear wall of the flame tube, the upper portion of which constitutes a part of the fuel conduit, extends downwardly beyond the inlet port and, in the present instance, into a boss 13 which depends from the flame tube beneath the inlet port. The lower end 55 of the bore is closed, in the present device by a screw 14, and thus constitutes a reservoir or equalizing chamber 21 which is in open communication with the fuel conduit and when the valve 3 is in its open position is in communication with the inlet port. The stem of the valve 3, which passes 60 through the portion 12 of the conduit and enters the inlet port 2, is of a diameter less than the diameter of the conduit so as to provide constant communication between the conduit and the reservoir. Arranged beneath the rear portion of the burner and, in the present instance, mounted on the supply pipe 6, is a generating cup 15 adapted 65 to receive a quantity of fuel which when ignited will heat the burner and vaporize the fuel in the reservoir and conduit. The flame tube is provided in the rear portion thereof with lateral openings, such as the side slots 16 and the smaller openings 17, 70 which provide air for mixture with the fuel, the number and size of these openings being determined by the requirements of the particular burner. The forward portion of the flame tube which projects beyond the transverse portion 10 of the conduit constitutes 75 what is known as a burner tip 18 and serves to guide the flame and cause it to be projected beyond the burner in the desired direction. The flame tube is also shown as 80

provided with rests or supports 19 and 20 by means of which a soldering iron or other implement may be supported on the tube with its end adjacent to the flame which is projected from the tip 18 thereof.

The burner is started in operation by pumping air into the tank 5 to place the fuel under air pressure and then opening the valve 3 to permit a portion of the fuel 10 to pass through the inlet port and the openings in the flame tube into the generating cup 15. This fuel is then ignited and the flame therefrom will heat the reservoir 13 and the rear end of the flame tube and thus 15 cause the fuel in the reservoir and fuel conduit to be vaporized. The valve 3 is preferably closed or partly closed during this initial vaporization and when the burner has been heated to the desired extent the 20 valve is opened to permit the vapor, which is under high pressure, to escape through the inlet port into the flame tube where it is ignited by the flame in the generating cup and where it mixes with the air and burns 25 with a blue flame of intense heat. The arrangement of the fuel conduit with relation to the flame tube is such that it is subjected to an intense heat which quickly converts the fuel into vapor under high pressure. 30 This intensely hot and completely vaporized fuel burns with a clear blue flame having an intense heat, which is the ideal sought for in burners of this type, but it has been found that the pressure fluctuates so that the fuel 35 is not fed uniformly to the flame tube, thus causing a flickering or "spitting" of the flame. This objectionable feature is overcome by providing the reservoir or equalizing chamber 21. When the pressure in the fuel conduit exceeds normal pressure the 40 excess fuel will be forced into the equalizing chamber and confined under pressure and, when the pressure in the fuel conduit drops, this fuel will escape to the inlet port 2, thus providing additional fuel and boosting the flame. In this manner the fluctuations in 45 pressure are avoided and a uniform flow of fuel is provided which results in a steady flame. Another result produced by this

construction of the burner is the constant 50 flow of fuel from the tank 5 to the burner. After the fuel in the tank has been initially subjected to air pressure a constant flow of fuel will be maintained to the burner until the tank is exhausted without the necessity 55 of repeatedly pumping air into the tank, as is usually necessary.

While I have shown and described one embodiment of my invention I wish it to be understood that I do not desire to be limited 60 to the details thereof as various modifications may occur to a person skilled in the art.

Having now fully described my invention, what I claim as new and desire to secure by 65 Letters Patent, is:

1. A burner of the character described, comprising a flame tube having a valve controlled inlet port at its rear end, a fuel conduit formed integral with said tube, extending transversely through the same, extending rearwardly through the upper wall thereof and downwardly through the rear wall thereof to said inlet port, and an equalizing chamber formed in the rear wall 75 thereof and communicating with said conduit.

2. A burner of the character described, comprising a flame tube having an inlet port in its rear end wall and having a boss depending therefrom beneath said inlet port, a fuel conduit formed integral with said flame tube, extending upwardly through the same, rearwardly along the top wall thereof and thence downwardly through the rear 80 wall of said tube into said boss, the lower end of said conduit being closed to form a reservoir beneath said inlet port, a needle valve extending through the last mentioned portion of said fuel conduit and adapted to 85 control said inlet port, that portion of said valve which extends through said conduit being of less diameter than said conduit to provide open communication between said conduit and said reservoir. 90

In testimony whereof, I affix my signature hereto.

LLOYD S. JOHNSON.
